UNITED STATES PATENT OFFICE.

GEORGE H. GUNDERSON, OF POTTER, NEBRASKA, ASSIGNOR OF ONE-HALF TO PATRICK MAGINNIS, OF KIMBALL, NEBRASKA.

ROAD DRAG.

Application filed June 15, 1922. Serial No. 568,553.

To all whom it may concern:

Be it known that I, GEORGE H. GUNDERSON, a citizen of the United States, residing at Potter, in the county of Cheyenne and 5 State of Nebraska, have invented a new and useful Road Drag, of which the following is a specification.

This invention relates to road drags, and has for its object the provision of a device 10 which will move the dirt from the sides of the road to the center with the scraping blades arranged successively and at such an angle that the rear blades will cover substantially the same width of roadbed as the 15 front blades, and whereby the drag will ride over ditches without upsetting.

The invention further contemplates the use of adjustable and reversible blades secured to the body of the drag with the body 20 being constructed of such material that the drag will not bounce over the roadbed when it meets with obstructions.

The invention will be best understood from a consideration of the following detailed description taken in connection with the accompanying drawing forming part of this specification, with the understanding, however, that the invention is not confined to any strict conformity with the showing 30 in the drawing, but may be changed and modified so long as such changes and modifications mark no material departure from the salient features of the invention as expressed in the appended claims.

35 In the drawing:—

Fig. 1 is a view in perspective of the road drag when being drawn over flat surfaces.

Fig. 2 is a bottom plan view of the road drag adjusted for treating crowned roadbeds.

40 Fig. 3 is a vertical section taken along the line 3—3 of Fig. 2.

Fig. 4 is a vertical section taken along the line 4—4 of Fig. 2.

45 The road drag, generally, comprises a pair of sections linked together with their rear adjacent portions adapted to be adjustably spaced whereby the road drag may be used for honing land for irrigation purposes, or 50 for roadbeds, and yet may be equally well used for smoothing crowned roadbeds, the depth of the drag being such, as compared to its width, that the drag will not ordinarily tilt when being drawn over ditches.

55 Referring to the drawing, 1, 2 and 3 des-

ignate transverse parallel frame bars having their ends located in staggered relation so that said ends will be offset relative to a line running centrally and longitudinally of the roadbed. A plurality of bars 4 and 5, 60 having their ends in abutting relation between pairs of the frame bars and located at right angles to said bars, space the frame bars from each other. The spacing bars 4 are secured at their opposite ends, respectively, to the frame bars 1 and 2, while the spacing bars 5 have their ends secured, respectively, to the bars 2 and 3. The two of the spacing bars 4 abutting one face of the central portion of the frame bars 2 are in alignment with the two spacing bars 5 abutting the opposite face of the central portion of the bar 2.

Diagonally disposed bracing bars 6 abut faces of the frame bars 2 and 3 at one end 75 and have their other ends beveled and secured, respectively, to the spacing bars 4 and 5, upon the outer side of a section of the drag, while brace bars 6^a are similarly employed on the inner side of each section. 80 These bracing bars are arranged at an acute angle to the frame bars 2 and 3, and form substantially the outer and inner sides of each section of the road drag.

Running substantially centrally of each 85 section and through perforations in the frame bars 1, 2 and 3, is a tie rod 7 firmly binding the three frame bars securely against the abutting ends of the spacing bars 4 and 5. Shorter tie rods 8, respectively bind 90 pairs of the frame bars together, such as 1, 2, and 2, 3, respectively. Running diagonally of the frame bars and through perforations in said bars and through perforations of certain of the spacing bars 4 and 5, are tie 95 rods 9 substantially parallel to the aligned brace bars 6 and 6^a. These tie rods further aid in reinforcing and securing the frame bars in position relative to the spacing bars. The tie rods 7, 8, 9, are arranged in different 100 horizontal planes and cross each other.

Secured upon the underside of the frame bars 1, 2 and 3 are wear plates 10. These plates have countersunk perforations in which are seated the heads of bolts 11 passing vertically through the frame bars and locked against removal by nuts on the threaded ends of the bolts. These bolts securely fasten the wear plates to the frame bars.

Mounted upon the lower portions of the forward faces of the respective frame bars 1, 2 and 3, are scraper blades 12 rigidly secured to the frame bars by means of bolts 13. 5 These blades are reversible and adjustable for wear. By means of the additional perforations 14 spaced above the perforations for the normal passage of the bolt 13, the blades may be lowered when their scraping 10 edges have been sufficiently worn.

The centrally disposed tie rod 9 of each section is provided with an eye 15 which provides means for securing the usual drag chains to the drag.

15 Upon the forward faces of the frame bars 1, and on the ends of the bars which are adjacent to each other are rigidly secured metal hinge plates 16 and 17. The plate 16 is provided with a hook 18 adapted to engage an eye 19 on the end of the plate 17 for pivotally connecting the adjacent ends of the frame bars 1 together.

On the outer faces of the rear frame bars 3 are secured metal plates 20 having hooks 25 21 adapted to receive links of the chain 22, whereby the rear inner ends of the sections may be variously spaced from each other, depending upon the length of the chain 22 engaged by the hooks 21. By employing such 30 means for adjustably spacing the rear ends of the sections from each other, the road drag is adapted to effectively hone crowned roadbeds, the spacing of the rear adjacent ends of the sections depending upon the 35 depth of the crown of the roadbed.

By providing the sections with a greater length than width and employing more than two blades, the road drag may be drawn over ditches without any possibility of upsetting 40 the drag, and by the use of wood in the construction of the sections, the drag will not bounce over the roadbed when it meets with an obstruction.

By making the blades 12 reversible and 45 adjustable, it will not be necessary to discard the blades when they have been worn to some extent.

The staggering of the ends of the frame bars 1, 2 and 3, provides for a diagonal disposition of the spacing bars 4 and 5, with 50 respect to the roadbed, whereby the drag will be pulled at substantially an angle of 45 degrees to a line running longitudinally of the center of the roadbed. Thus, the dirt 55 will be drawn from the edges of the roadbed towards the center and fill in the hollow places.

The angular disposition of the members comprising the sections of the road drag 60 causes the rear scraper blades to cover substantially the same width of the roadbed as the front blades.

What is claimed is:—

1. In a structure of the class described, 65 the combination of one or more sections each

comprising a plurality of transverse parallel frame bars having their ends located in staggered relation, a plurality of bars for spacing the frame bars and secured at right angles to said frame bars, brace bars connecting the ends of the frame bars, tie rods for binding the frame bars and the spacing bars in rigid relation with each other, and scraper blades mounted on the transverse frame bars. 75

2. In a structure of the class described, the combination of one or more sections each comprising a plurality of transverse parallel frame bars having their ends located in staggered relation, a plurality of bars for spacing the frame bars and secured at right angles to said bars, brace bars connecting the ends of the frame bars, tie rods for binding the frame bars and the spacing bars in rigid relation with each other, and scraper blades mounted on the transverse frame bars, certain of the tie rods being disposed parallel with the brace bars while others of the rods are disposed parallel with the spacing bars, and said tie rods being arranged in different horizontal planes and crossing each other. 80

3. In a structure of the class described, the combination of one or more sections each comprising a plurality of transverse parallel frame bars having their ends located in staggered relation, a plurality of bars for spacing the frame bars and secured at right angles to said bars, brace bars connecting the ends of the frame bars, tie rods for binding the frame bars and the spacing bars in rigid relation with each other, and reversible blades adjustably mounted on the frame bars. 95

4. In a structure of the class described, the combination of a pair of sections each comprising a plurality of transverse parallel frame bars having their ends located in staggered relation, a plurality of bars for spacing the frame bars and secured at right angles to said bars, brace bars connecting the ends of the frame bars, tie rods for binding the frame bars and the spacing bars in rigid relation with each other, and scraper blades mounted on the transverse frame bars, said sections having their forward adjacent ends pivotally connected together, with their rear adjacent ends adapted to be adjustably spaced from each other. 100

5. In a structure of the class described, the combination of a pair of sections each comprising a plurality of transverse parallel frame bars having their ends located in staggered relation, a plurality of parallel bars having their ends abutting the opposite faces of pairs of the frame bars and secured at right angles to said bars for spacing the frame bars, brace bars abutting the ends of certain of the frame bars with their other ends beveled and secured to certain of the 115 120 125 130

spacing bars, tie rods passing through the frame bars and rigidly binding the frame bars on the spacing bars, diagonally disposed tie rods passing through the frame 5 bars and the spacing bars and supplementing the first-mentioned tie rods for maintaining the frame bars in rigid relation with the spacing bars, scraper blades adjustably secured to the lower ends of the 10 frame bars, and means for connecting the adjacent inner ends of the sections together.

6. In a structure of the class described, the combination of one or more sections, each 15 section comprising a plurality of parallel frame bars consecutively spaced in offset

relation, a plurality of bars secured at right angles to and between pairs of the frame bars, tie rods passing through the frame bars and rigidly binding said bars to the spacing bars, diagonally disposed tie rods 20 passing through the frame bars and the spacing bars at a different horizontal plane than the first-mentioned tie rods and crossing the same and providing an additional securing means for the frame and spacing 25 bars, and scraper blades secured to the frame bars.

In testimony that I claim the foregoing as my own, I have hereto affixed my signature.

GEORGE H. GUNDERSON.
